UNITED STATES PATENT OFFICE.

MAYER REINFELD, OF ST. LOUIS, MISSOURI.

DESIGN FOR A LOOKING-GLASS FRAME.

SPECIFICATION forming part of Design No. 22,392, dated May 2, 1893.

Application filed February 24, 1893. Serial No. 463,644. Term of patent 14 years.

To all whom it may concern:

Be it known that I, MAYER REINFELD, a citizen of the United States, residing at St. Louis, State of Missouri, have invented and 5 produced a new and original Design for Looking-Glass Frames, of which the following is a specification, reference being had to the accompanying drawing, showing a part thereof.

The figure is a front elevation of a looking-glass frame constructed according to my design.

The leading feature of my design is a looking-glass frame the sides of which are provided with a series of suitable columns, the 15 said columns being confined between sockets each containing a suitable rosette.

It also consists in providing such a frame with a top portion which is composed of a series of short tubes, a mirror back ground for 20 the same and the whole capped by suitable scroll work.

In the drawing, 1 represents a series of mirrors, and 2 represents a series of columns or pillars. The columns are disposed on 25 either side of the mirror 1 and at either end of the set of columns are disposed rosettes 4 surrounded each by a suitable plate 5. Between the lower series of rosettes and consti-

tuting the base for the frame are suitable base pieces 6.

The top of the mirror frame may be described as containing a lower plate 7 running the full length of the frame, with a suitable number of rosettes 8 disposed thereon, one over each rosette 4 of the body portion of 35 the frame, and one rosette over the center of the mirror. Capping the lower plate 7 of the top of the frame is disposed a series of tubes 9. In the rear of said tubes is a mirror running the full length of the frame, said 40 mirror being designated by the numeral 10 in the drawing. The said tubes and mirror 10 are capped by scroll work 11. The plate 7 above referred to has a reflecting surface as also the small plates 5 surrounding the rosettes 4.

Having described my invention, what I claim is—

The design for a looking-glass frame substantially as set forth.

In testimony whereof I affix my signature in the presence of two witnesses.

MAYER REINFELD.
